UNITED STATES PATENT OFFICE.

NAUM SHAMUS-GORGIS BESHAROV, OF PATERSON, NEW JERSEY.

TUMBLER FOR COMBINATION-LOCKS.

1,156,741.

Specification of Letters Patent. Patented Oct. 12, 1915.

Application filed November 28, 1914. Serial No. 874,406.

To all whom it may concern:

Be it known that I, NAUM S. G. BESHAROV, a subject of the Czar of Russia, and a resident of Paterson, in the county of Passaic and State of New Jersey, have invented a new and Improved Tumbler for Combination-Locks, of which the following is a full, clear, and exact description.

This invention relates to improvements in combination locks of the type disclosed in United States Letters Patent Number 1,046,253, granted to me December 3, 1912, and the invention has to deal more particularly with improvements in the construction 15 of the tumblers for such combination locks.

The invention has for its general objects to improve and simplify the construction of tumblers for combination locks so as to be more reliable and efficient in operation and 20 inexpensively and expeditiously manufactured and assembled.

With such objects in view and others which will appear as the description proceeds, the invention comprises various novel 25 features of construction and arrangement of parts which will be set forth with particularity in the following description and claims appended hereto.

In the accompanying drawing, which 30 illustrates one embodiment of the invention and wherein similar characters of reference indicate corresponding parts in all the views, Figure 1 is an elevation of a lock with portions broken away to illustrate the tumbler 35 mechanism and the bar controlled thereby that in turn controls the throwing of the bolt of the lock; Fig. 2 is a plan view of one of the tumblers, Fig. 3 is a sectional view on the line 3—3, Fig. 2; Fig. 4 is a perspective 40 view of the cover plate of the tumbler; Fig. 5 is a plan view of the bottom plate of the tumbler with several of the spring-actuated gates and gate catches assembled; Fig. 6 is a plan view of the bottom and intermediate 45 plates, part of the latter plate being broken away, and Fig. 7 is a detail view showing one of the gates and the key recess controlled by the gate.

Referring to the drawing, A designates 50 the casing of a combination lock which contains the tumbler mechanism B for controlling the throwing of the bolt 2 of the lock, this controlling being effected by the tumbler mechanism B acting on a bar 3 which 55 has a key 4 which prevents movement of the bar 3 unless the various tumblers 5 are in a

predetermined position with certain gates in alinement so that the key can pass into engagement successively with the alining gates to throw the same open, as will be understood by reference to the patent hereinbefore referred to. On the bar 3 are stops 6 and 7 that coöperate with the tumblers when the bolt is in locking position and the tumblers then shifted, whereby such stops form barriers for engaging the tumblers or their closed gates to prevent the key-carrying bar 3 from being moved to effect the unlocking of the bolt. These parts are of usual construction so that more detailed explanation is deemed unnecessary.

Each tumbler is composed of three plates 8, 9 and 10 which are of circular form and are fastened together to form means for holding the gates 11 and the gate catches 12. 65 The bottom plate 10 is fastened to an encircling ring 13 which is of larger diameter than the plates 8, 9 and 10 so that between the latter and ring an approximately circular slot 14 is formed through which the key-carrying portion of the bar 3 extends. The ends of this slot are formed by a web 15 on the plate 10 which connects with the ring 13, and consequently the tumbler cannot make one complete revolution. The plate 10 has 70 a central opening which is threaded to receive a bushing 16, which bushing receives the axle 17 on which the tumblers turn. The end of the bushing 16 opposite from the plate 10 enters an opening 17' on the top plate 8. The intermediate plate 9 is fastened to the plate 10 by screws 18 and the plate 8 is fastened to the plate 9 by screws 19. Confined between the intermediate plate 9 and bottom plate 10 are radially 75 movable gates 11 which slide in guideways formed by approximately semi-cylindrical grooves 21 in the plate 10 and corresponding grooves 22 in the plate 9. These gates are of 80 round cross-section and each has a lug 23 on its inner end that engages the outer end of a radial slot 24, whereby the outer movement of a gate is limited. Between the inner end of each gate and the hub-forming bushing 16 is interposed a helical spring 25 which 85 urges the gate outwardly, but its movement is limited by the lug 23.

Associated with each gate is a catch 12 that is slidable transversely to its associated gate, so that when the latter is pressed inwardly the catch will spring outwardly in front of the gate and hold the same re-

tracted, there being behind each catch a spring 27. The catch 12 and coacting spring 27 are set in a pocket or recess 28 formed in each tooth 29 in the plate 10. The teeth 30 on the middle plate 9 have openings 31 which register with the recesses 28. On the teeth 32 in the plate 8 are projections 33 which enter the openings 31 of the plate 9, whereby the spring and catches are properly held in place. When the several plates are put together after the gates 11 and their springs and the catches 12 and their springs are assembled, the teeth of the various plates register, so that a plurality of radial slots or recesses 34 are formed, each having a gate 11, and through any one of these recesses the key 4, Fig. 1, is capable of passing when the tumblers or tumblers occupy a predetermined position. It is to be noted that the plate 8 is of smaller diameter than the plates 9 and 10, as the lower end of the key 4 and the stop pins 6 and 7 are adapted to lie in the same plane with the plates 8 of the respective tumblers when the bolt is in locking position, as shown in Fig. 1, these pins serving to act as bafflers to prevent the unlocking of the bolt by any one who does not know the proper combination for the tumblers.

30 To insure easy movement of the gate 11 inwardly when the key 4 engages the same, the side of each recess 34 opposite from that side from which the catch 12 projects, is formed with a shallow groove 34^a, Fig. 7, and the gate 11 bears therein so that there is no possibility of the gate binding by being canted or tilted as the key 4 engages and wipes transversely past it. To permit the tumblers B to rotate with a minimum of friction, washers 35 are interposed between the tumblers and arranged on the axle 17.

40 From the foregoing description taken in connection with the accompanying drawing, the advantages of the construction and method of operation will be readily understood by those skilled in the art to which the invention appertains, and while I have described the principle of operation, together with the device which I now consider to be 45 the best embodiment thereof, I desire to have it understood that the device shown is merely illustrative and that such changes may be made when desired as are within the scope of the appended claims.

50 Having thus described my invention, I claim as new and desire to secure by Letters Patent:

1. A tumbler for a combination lock comprising a ring, a circular body disposed within and connected with the ring, there being an approximately circular slot between the ring and body, said body being made of a plurality of plates separably connected and provided with radial slots lying in the 60 plane of division of the plates, sliding gates

in each slot and of round cross-section, a spring behind each gate for forcing the same outwardly, a projection on each gate and arranged to engage one of the plates to limit the outward movement of the gates, and 70 spring-pressed catches arranged within the body to engage the gates when in open position, said body having in its periphery recesses into which the gates normally extend and through any one of which a key 75 is adapted to pass to force the gate open while the bolt of the lock is being thrown to locking position, the catch of the open gate being automatically released by the key during its return movement. 80

2. A tumbler for a combination lock to control the operation of the bolt thereof, said tumbler comprising a body having one or more recesses through which a key is adapted to pass during the throwing of the 85 bolt to and from locking position, said body being made of separably connected plates each having oppositely-disposed grooves forming guideways, gates slideable in the said guideways and of round cross-section and 90 adapted normally to close the recesses of the body, means for urging the gates outwardly, stops on the gates arranged to engage one of the plates to limit the outward movement of the gates, and spring-pressed catches 95 arranged in the body and adapted to be automatically projected into engagement with the gate when the latter is in open position and to be automatically released by a key passing the open gate in order to permit the 100 gate to return to normal position when the key has passed.

3. A tumbler of the class described comprising inner and outer plates, a hub on one of the plates and extending through the 105 other plates, said plates having their peripheries provided with registering recesses, sliding gates mounted between two of the plates to normally close the recesses, springs interposed between the gates and said hub 110 for normally holding the gates outwardly, spring-pressed catches mounted in one of the outer plates, whereby any gate will be held in open position, there being openings in the middle plate registering with the 115 spring-pressed catches, and projections on the other outer plate to enter the openings of the inner plate for holding the spring-pressed catches in place.

4. In a combination lock, the combination 120 of a key-carrying element movable with the bolt of the lock, a plurality of spaced projections thereon, a key on the element spaced from the projections, a plurality of tumblers movable with respect to each other 125 and to the said element, a plurality of spring-pressed gates on each tumbler, means carried by the tumbler whereby a gate when thrown open by engagement with the key is automatically held in open position, said 130

tumblers each having its rim and body portion of the same thickness axially and the body portion being made of separable plates, and one of the plates at each tumbler being of smaller diameter than the others, whereby the projections and one extremity of the key can lie in the same plane with the smaller plates of the tumblers when the key-carrying element is in a position corresponding to the locking position of the bolt.

5. In a combination lock, a tumbler having a recess through which a key is adapted to pass, a sliding gate in the tumbler and normally closing the recess, and a catch in one side of the recess to engage and hold the gate in open position, said gate being of round cross-section and the side of the recess opposite from the catch having a 10 guide groove in which the gate slides.

6. In a combination lock, a tumbler having a recess through which a key is adapted to pass, a sliding gate of round cross-section in the tumbler and extending into the recess and adapted to yield inwardly by the 15 key wiping transversely past the gate, a catch at one side of the recess for engaging and holding the gate in open position after being moved to such position by the key, and guide means at the side of the recess 20 opposite to the catch and with which gate slidably engages.

In testimony whereof I have signed my name to this specification in the presence of two subscribing witnesses.

NAUM SHAMUS-GORGIS BESHAROV.
